UNITED STATES PATENT OFFICE

137,928

DESIGN FOR A LAWN MOWER

Earl L. Schofield, Auburn, Ind., assignor to The Atwood Vacuum Machine Company, Rockford, Ill., a copartnership composed of Seth B. Atwood and James T. Atwood

Application May 26, 1943, Serial No. 110,302

Term of patent 14 years

(CL. D40—1)

To all whom it may concern:

Be it known that I, Earl L. Schofield, a citizen of the United States, residing at Auburn, in the county of De Kalb and State of Indiana, have invented a new, original, and ornamental Design for a Lawn Mower, of which the following is a specification, reference being had to the accompanying drawings forming part thereof.

In the drawings:

Fig. 1 is a front perspective view of a lawn mower showing my new design;

Fig. 2 is a rear perspective view thereof;

Fig. 3 is a side view thereof on a slightly enlarged scale and with a portion of the handle broken away for convenience of illustration, and

Fig. 4 is a top plan view thereof following illustration and scale of Fig. 3.

The essential features of the design are shown in full lines on the drawings.

I claim:

The ornamental design for a lawn mower, substantially as shown and described.

EARL L. SCHOFIELD.
